UNITED STATES PATENT OFFICE.

ROBERT REID, OF BEVERLY, MASSACHUSETTS, ASSIGNOR OF ONE-HALF TO ANDREW S. REID, OF BEVERLY, MASSACHUSETTS.

LASTING-MACHINE.

1,261,959.

Specification of Letters Patent.

Patented Apr. 9, 1918.

Application filed June 7, 1915. Serial No. 32,476.

To all whom it may concern:

Be it known that I, ROBERT REID, a citizen of the United States, residing at Beverly, county of Essex, State of Massachusetts, have invented a certain new and useful Improvement in Lasting-Machines, of which the following is a specification, reference being had therein to the accompanying drawings.

10 My invention has for its object a new and improved machine for lasting shoes, the particular object being to make it possible to stitch the upper directly to the insole while the upper is still under the tension exerted 15 upon it by the lasting machine; also to make it possible to do away with the use of tacks by means of which the upper is secured to the last after having been lasted; also with the tacks by which the insole is temporarily 20 secured to the last.

In a machine embodying my invention the upper is put into the machine, the last is put in place and the machine then stretches the upper over the last and into position adjacent the insole, holding it firmly in position. The machine is so constructed that a separable and portable unit is provided, including a last, air bag, and receptacle therefor, so that after the lasting has been done 25 the said parts together with the insole and upper, the upper having been stretched into proper position and being still under tension, may be removed bodily, and carried to a suitable fastening machine by means of 30 which the upper and insole are secured together. The machine is so constructed that the insole is held in proper position on the last by the machine itself thereby doing away if desired with the necessity of tacking the insole temporarily to the last. For 35 the purpose of stretching the upper over the last and retaining it in place after it has been stretched and until the fastening takes place, I employ pneumatic pressure conveyed from an air reservoir to said air bag. I am aware that it has been proposed to use 40 pneumatic pressure to last shoes, but the proposed devices have not been constructed so as to force the edges of an upper out over the edge of an insole sidewise and therefore 45 are wholly incapable of stretching the

leather properly, as is done by the ordinary mechanical lasting machine, or by a workman. Furthermore, no provision has been made to enable the insole and upper to be 55 united while the upper is still under tension.

In this specification I have referred to fastening mechanism, by the operation of which the upper and insole are secured together. I do not limit myself to stitching 60 mechanism, as other means may be employed and are included in the term fastening mechanism.

I believe myself to be the first to devise a lasting machine in which the insole is positioned by means of a member contacting with the bottom of the insole at a point well within and away from the line along which the upper and insole are united by stitching or otherwise, in order that the parts of the 70 shoe may be secured together without the support interfering with the operation of securing the parts together. I am also the first to combine said means with means to stretch the upper by pneumatic pressure, and 75 to hold it in position as long as required, thus, if desired permitting the lasted shoe to be carried around the shop to various machines such as sewing, nailing, screwing machines, etc., to fasten the sole to the upper 80 and to be readily handled by the operator to present the proper portions of the work to the machine, the shoe being still under pneumatic pressure. This system of lasting 85 shoes and of securing the upper to the sole I believe to be novel.

The parts are also so combined that during the operation of securing the upper to the sole, the receptacle, air bag, last and shoe can be turned while the support is holding 90 the sole in position on the last, and is holding the shoe lasted, thus enabling the operator to present the proper portions to the machine.

These and other novel features of this invention will be claimed in the claims appended hereto.

In the accompanying drawings I have shown my invention in the form which I consider to be the best but it will be understood that it is readily capable of modification and I do not limit myself to the particu-

lar form shown as the invention is a broad one.

Referring to the drawings, Figure 1 is a front elevation of a device embodying my 5 invention.

Fig. 2 is a vertical section of the last holder and attached parts.

Fig. 3 is a transverse section thereto.

10 Fig. 4 is a top plan view of the said parts. Fig. 5 is a transverse section similar to Fig. 3 but showing the air bag expanded by the pressure.

In the drawings, and in the preferred embodiment of my invention, at A is shown 15 a base and at B a table. At 11, is shown a bracket provided with two holes 12, 12, to receive dowels or pegs 13, 13 in the top of the table B so that the unit of which the bracket forms a part may be quickly and 20 conveniently detached from the table.

At 14 is shown the last holder having a hollow space therein within which projects a spindle 15 on which is received the last 16. The last holder 14 has an opening 17 of the 25 general size and shape of the bottom of the shoe to be lasted, but slightly larger. The side edges *a* of the said last holder project inwardly toward the last on a level about that of the bottom of the last. The opening 30 or space between the last and the interior of the last holder is narrower or constricted around the edge of the last. The last holder is made conveniently of aluminum or other light material to make it convenient to 35 handle.

At 18 is shown a downwardly projecting tube or stem provided with a shoulder 19. The stem 18 passes down through a hole in the bracket 11 and a corresponding hole in 40 the table B. The upper arm of the bracket 11 is so located as to project over the center of the ball of the last and is forked at its end as shown at 20 to form bearings to receive a swinging pin 21 pivoted on trunnions 22 in the said bearings.

The bracket and the swinging pin together form what I term the support. This support performs the two fold function of 45 positioning the insole on the last, this function heretofore having been performed by tongs, etc., and of resisting the pressure exerted on the last by the lasting instruments. The swinging pin permits the support to be instantly adjusted against the insole.

Between the last 16 and the last holder 14 and covering an area approximately that of the upper is placed a hollow elastic air bag 23 connected by a tube 24 and separable 60 connection 25 with an air pipe 26 leading to an air tank 27 or other suitable source of supply of air under pressure. Said tube 24 extends downwardly through the stem 18.

The air bag 23 is of varying cross section 65 transversely being thinner at the center as

shown at *b* in Fig. 3 and thicker toward the sides as shown at *c c*. The side edges as shown at *d d* are also relatively thick. This construction is such that when at rest the side edges *d d* will be at a point considerably below the bottom of the last and the inturned edge *a* of the last holder, and that, when air under pressure is admitted, the air bag will stretch laterally beginning at the center where it is weakest and continuing 75 until the edge *d* is forced into the space between the inturned edge *a* of the last holder and the edge of the last. It will be seen that the tendency is therefore for the air bag to work the upper sidewise from the 80 median line toward the edges thus lasting the upper with absolute nicety and perfection. At 28 is shown a valve by means of which the escape of air from the interior of the air bag is prevented, said valve being 85 provided with a stem 29 by means of which it may be opened when it is desired to release the pressure. At 30 is shown a valve by means of which the supply of compressed air from the tank is controlled. The separable connection 25 affords means by which the air bag may be quickly detached from the air reservoir, the air in the air bag being 90 retained by the valve 28. It will be seen that the hinged member 21 is directly in line 95 with the stem 18 of the last holder 14 so that the last holder and last may be swung about their common axis when desired without releasing the shoe from the pressure exerted on the upper by the air bag. It will be 100 seen that the member 21 contacts with the insole at a point well within the line of union between the upper and insole to permit the two being operated upon by a machine as for instance a sewing machine, 105 while still under pressure. It will also be seen that when it is desired to take the shoe out, this may be easily accomplished by releasing the pressure on the air bag by means of the valve 29. In the operation of my 110 machine in the form shown in the drawings, the bracket and last holder are put in place on the table B. The air pipe 26 is connected with the tube 24. The insole is then laid on the bottom of the last and the upper 115 put in place. The last is then inserted in the last holder on the peg 15 and the hinged member 21 turned down into contact with the insole, thus holding the insole in its proper position. Air is then admitted by 120 the valve 30 and fills the air bag expanding it. This causes the edges of the air bag to force themselves up into the constricted space between the inturned edges *a* of the last holder and the adjacent portion of the 125 last stretching the upper forcibly sidewise and retaining the whole in position so long as the air pressure is maintained in the air bag. The parts are then in the position shown in Fig. 5. The connection 25 is then 130

- severed but the pressure does not escape from the air bag being retained therein by the check valve 28. The upper may then be tacked or the unit comprising the last holder, 5 insole support, air bag, last and shoe thereon may be lifted bodily from the table B and taken to the fastening machine by means of which the upper and insole may be permanently secured together. The fastening 10 may be done in any suitable manner as by stitching or metal fastening. If desired the upper may be tacked to the last in the manner previously employed and the stitching done subsequently, but under ordinary conditions it is more economical and exactly 15 satisfactory to stitch the upper to the insole at once without going through the unnecessary and expensive operation of tacking. The method of fastening will of course vary 20 with the kind of shoes to be made—whether Goodyear welt, turn, McKay, Standard screw, etc.

During the stitching operation the last and last holder can be swung relatively to the support as required thus giving more convenient access to the portion of the shoe to be stitched. The air pressure is not released until after the stitching has been done.

- 25 30 As the parts composing the unit can be made of light metal or similar material they are easy and convenient to handle.

What I claim is:

1. A lasting machine including an air 35 bag to contact with the vamp and quarters of the shoe to be lasted, said air bag being of a shape to fit about the said vamp and quarters and being thinner at that portion which lies adjacent the median line of the 40 vamp of the shoe and being thicker elsewhere whereby the stretching of the air bag begins along said line.
2. The combination of a last, and a last 45 holder surrounding the portion of the last on which the upper is to be lasted and an air bag interposed between the said upper and the said last, said air bag being thinner along the median line of the last than it is elsewhere.
3. A pneumatic lasting machine comprising a last, means for holding the last substantially rigid, a last holder, and an air bag interposed between said last and said last holder, said air bag being thinner at the 55 center and thicker at the edges whereby a sidewise stretching of the upper is produced.
4. A pneumatic lasting machine comprising a last, a last holder, an air bag interposed between the last and the last holder, and a support acting in opposition to the pressure exerted by the air bag and at a point within the line of stitching about the 60 edge of the shoe.
5. A pneumatic lasting machine comprising a last, and a member about said last and having a chamber therein for the reception of fluid under pressure, said member having a flexible wall adjacent the last and a support acting in opposition to the pressure exerted by the fluid within the said chamber and at a point within the line of stitching about the edge of the shoe.
6. A pneumatic lasting machine comprising a last, a last holder, an air bag interposed between the last and the last holder, a support opposite the bottom of the last and adapted to prevent movement of the last away from the last holder, and means for supplying air under pressure to the 70 interior of the air bag.
7. A pneumatic lasting machine comprising a last, a last holder, an air bag interposed between the last and the last holder, a support opposite the ball of the last contacting with the insole on the last and adapted to prevent movement of the last away from the last holder and to hold the insole in position on the last, and means for supplying air under pressure to the 80 interior of the last holder.
8. A pneumatic lasting machine comprising a last, a last holder, an air bag interposed between said last and said last holder, and means contacting with the insole on the 85 last to prevent movement of the last away from the last holder when air under pressure is admitted to the last holder, said means being rotatable relatively to the last, last holder, and air bag to give access to the 90 edge of the insole to permit the fastening operation to be performed.
9. A pneumatic lasting machine comprising a source of air under pressure, a tube 105 connected therewith, an air bag, a detachable connection with said air bag, a valve to prevent the escape of air from the air bag, a last, and a last holder, said air bag being interposed between said last holder and the last, said last, air bag, and holder forming 110 a separable unit which may be carried to another machine by which the insole and upper will be secured together.
10. The improved lasting machine comprising a bracket, a last holder rotatable 115 relatively to the bracket and having a cavity therein, a last, an air bag in said cavity, said air bag being interposed between said last holder and the said last, and a support for holding the last in line with the axis of rotation of the last holder on the bracket.
11. The improved lasting machine comprising a bracket, a last holder having a cavity therein of the general shape of the last, and having a stem extending through 125 said bracket and on which said last holder is rotatable relatively to said bracket, a last in said cavity, an air bag interposed between the said last holder and the said last and an air pipe extending through the stem of 130

said last holder, said last holder being rotatable on said stem.

12. The combination of a last, a last holder surrounding a portion of the last on which the upper is to be lasted, and an air bag interposed between the said upper and the said last, said last holder being provided

with inturned edges closely adjacent the bottom surface of the last and forming with the last a constricted opening around the 10 edge of the last.

In testimony whereof I affix my signature.

ROBERT REID.
